Fig. 6

Fig. 8

Fig. 9

Fig. 7

FIG. 1 is a front elevation of a cordless vibrating massager showing my new design;

FIG. 2 is a top perspective view thereof;

FIG. 3 is a side elevation thereof;

FIG. 4 is a bottom plan view thereof;

FIG. 5 is a top plan view thereof;

FIG. 6 is a front elevation of a modified embodiment of the massager illustrated in FIG. 1;

FIG. 7 is a top perspective view thereof;

FIG. 8 is a side elevation thereof; and

FIG. 9 is a top plan view thereof.

I claim:

The ornamental design for a cordless vibrating massager, substantially as shown and described.
